L. H. PRAY,
PNEUMATIC ACTION FOR PIANOS,
APPLICATION FILED JAN. 14, 1921.

1,413,612.

Patented Apr. 25, 1922.

Inventor:
Louis H. Pray,
by Walter E. Lombard,
Atty.

UNITED STATES PATENT OFFICE.

LOUIS H. PRAY, OF MEDFORD, MASSACHUSETTS.

PNEUMATIC ACTION FOR PIANOS.

1,413,612.

Specification of Letters Patent. Patented Apr. 25, 1922.

Original application filed August 10, 1920, Serial No. 402,648. Divided and this application filed January 14, 1921. Serial No. 437,291.

To all whom it may concern:

Be it known that I, LOUIS H. PRAY, a citizen of the United States of America, and a resident of Medford, in the county of 5 Middlesex and State of Massachusetts, have invented certain new and useful Improvements in Pneumatic Actions for Pianos, of which the following is a specification.

This invention relates to pneumatics for 10 player pianos and has for its object the provision of a unit pneumatic which may be secured in any desired position upon a supporting bar.

The invention consists also in certain 15 novel features of construction and arrangement of parts which will be understood readily by reference to the description of the drawings and to the claims to be hereinafter given.

20 The present invention is a division of another application of mine filed August 10, 1920 and numbered 402,648.

For the purpose of illustrating the invention, one preferred form thereof is illustrated in the drawings, this form having been found to give satisfactory and reliable results although it is to be understood that the various instrumentalities of which the invention consists can be variously arranged 25 and organized and the invention is not limited to the precise arrangement and organization of these instrumentalities as herein shown and described, except as required by the scope of the appended claims.

30 Of the drawings:

Figure 1 represents a side elevation of a unit embodying the principles of the present invention applied to a supporting bar shown in section.

40 Fig. 2 represents a vertical section of the same.

Fig. 3 represents a horizontal section on line 3, 3, on Fig. 2.

Fig. 4 represents a horizontal section on 45 line 4, 4, on Fig. 2.

Fig. 5 represents a plan of a portion of the supporting bar and the supports therefor showing a unit secured to said bar, and

50 Fig. 6 represents a front elevation of the same, portions of which are shown in section.

Similar characters indicate like parts throughout the several figures of the drawings.

In the drawings, 10 is a metal bar provided with a longitudinal V-shaped upward bend 11 extending longitudinally thereof.

The front edge of said bar is provided with a downwardly extending flange 12 while the rear edge thereof is provided with a downwardly extending L-shaped flange 13.

This bar may be cut in any suitable length to accommodate it to various styles and sizes of pianos.

Each end of the bar 10 is provided with a slot 14 preferably extending to the outer end thereof.

Positioned in the slot 14 is a clamping bolt 15 mounted in the horizontal portion 16 of a bracket 17 having a vertical slot 18 therein.

In the vertical slot 18 are one or more clamping members 19 mounted in the fixed member 20 which may be the side wall of a piano or a portion of a framework mounted in said piano.

By means of this construction the supporting bar 10 may be adjusted vertically to locate it properly for the actuating parts of the piano action.

By adjustment of the supporting bar on 80 the end brackets 16, 17, the bar may be accommodated to various lengths of pianos.

When once adjusted the supporting bar 10 is securely clamped to the horizontal portion 16 of the bracket 17 and the said brackets 17 are securely clamped to the members 20 at the opposite ends of the piano.

Only one end of the bar and its supporting bracket is shown in the drawings, it being believed to be unnecessary to show the 90 entire length and the construction at the opposite end as this construction is simply a duplication of the construction shown in Figs. 5 and 6 of the drawings.

The front flange 12 of the supporting 95 bar 10 is adapted to be positioned in a transverse slit 21 in the upper face of a block 22 while the horizontal portion of the rear L-shaped flange 13 is adapted to extend into a groove 23 in the rear end of the block 22.

The upper face of the block 22 has secured thereto, a pad 24 of felt or some similar yielding substance which pad extends over the end of the said block and into the upper part of the groove 23 as indicated in 100 Fig. 2 of the drawings.

When the block is positioned relatively to the supporting bar 10 as indicated in Figs.

1 and 2 of the drawings, the pad 24 is slightly compressed and thereby causes sufficient friction between the two members to prevent one accidentally moving relatively 5 to the other.

By means of a screw or other holding member 25, a spring clip 26 is secured to the upper face of the forward end of the block 22, this clip extending toward the rear 10 of the block 22 and being adapted to engage with the highest part of the V-shaped bend 11 thereby firmly retaining the block 22 in position on said supporting bar 10.

The blocks 22 may be adjusted longitudinally of the supporting bar 10 and when moved into any desired position thereon they are retained in such adjusted position by means of the spring clip 26 and the front and rear flanges 12 and 13.

When it is desired to remove the block 20 from the supporting bar, a downward pressure upon the front end of the block will cause the spring clip 26 to yield sufficiently to allow the front flange 12 to be removed 25 from the transverse slit 21 and when said flange has been removed, a forward pull upon the block 22 will disengage the block from the L-shaped rear flange 13.

It is obvious therefore, that the blocks 22 30 may be moved upon the supporting bar into any desired position to accommodate them to the various styles of piano actions and retained in adjusted position without using securing screws or other members which 35 must be removed when it is desired to remove a block for any reason.

Each block is a separate unit and may be removed from the supporting bar without disturbing any of the other units and as 40 means is provided whereby such removal may be made toward the front of the piano, the other parts of the operating device will not be disturbed.

The block 22 itself is preferably made up 45 of a plurality of layers of material.

The upper layer 27 of the block 22 is provided with a cylindrical port 28 opposite the V-shaped bend 11 in the supporting bar 10.

Air is adapted to enter through the port 50 28 into a chamber 29 formed in the layer 30 immediately beneath the layer 27.

This layer 30 has also formed therein a passage 31 communicating with aligned cylindrical openings 32 formed in the middle 55 layer 33 and the lower layers 34 and 35.

The opposite end of the passage formed by said cylindrical openings 32 communicates with a bellows or pneumatic hinged at 36 to the lower layer 35 and composed in 60 part of a movable plate 37 connected to the edge of the lower layer 35 by means of a flexible member 38.

The rear end of the hinged movable plate 37 is provided with a projecting member 39 65 adapted to communicate with and actuate a

vertical rod for operating the hammer of the piano action.

In the layer 33 and aligned with the port 28 is a connecting port 40, the lower end of which communicates with a chamber 41 70 from the forward end of which extends a passage 42 communicating with a passage 43 in the upper end of which is a tubular member 44, the upper end of which is adapted to receive a flexible tube 45 of rubber or 75 some similar material, the opposite end of which extends to and communicates with the usual vacuum chest.

The upper face of the lower layer 35 is provided with a depression 46 with the forward end of which communicates a passage 47. A tubular metal pipe 48 communicates with the forward end of the passage 47 and has an upward bend therein the upper end of which is adapted to receive one end of 85 a flexible tube 49 of rubber or some similar material, the opposite end of which communicates with one of the openings in the usual tracker board.

The upper end of the depression 46 is 90 closed by a flexible diaphragm 50 secured at its edge to the upper face of the layer 35 and superimposed upon this diaphragm 50 and preferably secured thereto is a stiffening plate 51 having an upwardly extending post 52, the upper end of which projects through the connecting port 40 with its extreme upper end slightly below the upper surface of the layer 33.

This layer 33 has extending upwardly 100 therefrom, a plurality of guide pins 53 between which is a disk valve 54, the upper and lower faces of which are faced with rubber 55 as indicated in Fig. 2 of the drawings.

Between the passage 47 and the passage 42, is a port 56, the upper end of which is closed by a disk 57 having a small central vent as shown in Figs. 2 and 3 of the drawings.

This vent is so located that it can readily be cleaned of dust or any other obstructions by removing the rubber tube 45 from the tubular member 44 and extending a needle downwardly through said tubular member 115 44 into the vent 58.

This is of some importance as devices of this class are liable to become inoperative by being clogged with dust and it is desirable to provide means for readily cleaning out the passages without disturbing the various operating parts.

By making the block 22 of a plurality of laminated layers, the construction of the block is greatly facilitated as each layer may 125 be quickly provided with the various ports, chambers and depressions and then all of the layers may be assembled and glued together making a suitable block.

When these layers have been thus secured 130

together, the sides thereof have glued thereto, sheets 59 of fibre-board or some similar material.

The operation of the device is as follows:

5 A piano having been selected, the brackets 17 are secured to end frames 20 and adjusted vertically so that the supporting bars 10 will be at the desired height and these supporting bars 10 are adjustably secured 10 to the brackets 17 so that said bars extend the entire length of the piano.

While only one bar 10 is shown in the drawings, it is obvious that in installing the player mechanism two supporting bars 15 would be used one above the other.

A unit is then selected for each string of the piano and these are mounted upon the supporting bars 10 and adjusted lengthwise thereof so that the member 39 of each unit 20 will be in position to actuate a hammer actuating rod forming a part of the piano action.

The various units are then connected by means of the rubber tubes 45 and 49 to the 25 vacuum chest and the tracker board.

When thus connected and one of the openings in the tracker board is uncovered or exposed, air will be admitted to the tubular member 48 and passing through the passage 47 and depression 46 will force the diaphragm 51 upwardly and thereby cause the post 52 to lift the valve 54 and close the port 28 while uncovering the port 40.

As a consequence of this lifting of the 35 valve 54, a communication from the vacuum chest is made through the tubular member 44, passages 43 and 42, chamber 41, port 40, chamber 29, passages 31 and 32 to the interior of the pneumatic or bellows 40 37—38 secured to the lower portion of the block 22.

The suction through these passages and chambers will thereupon cause the bellows to be collapsed and the projection 39 from 45 the rear end of the plate 37 will be consequently moved upwardly to actuate the hammer of the piano action.

When the tracker board opening is again covered, the pneumatic or bellows 37—38 50 returns to its normal position the air beneath the diaphragm 51 being discharged through the vent 58 thus permitting the diaphragm 51 to move downwardly together with the post 52.

55 The lowering of the post 52 will permit the valve 54 to drop into the position indicated in Fig. 2 of the drawings and then atmospheric air will pass through the port 28, chamber 29, passages 31, 32 into the interior of the bellows or pneumatic 27—38 60 returning the plate 37 of said pneumatic to its lowermost position as indicated in Fig. 2 of the drawings preparatory to another operation thereof.

65 This makes a simple construction of unit

which may be made economically and the means provided for mounting the various units upon a supporting bar is most effective.

It is believed that from the foregoing description, the operation and many advantages of the present invention will be readily understood.

Having thus described my invention, I claim—

1. A laminated pneumatic unit constructed of a plurality of layers of material and provided with a plurality of air chambers and passages; valve mechanism therein controlling the passing of air through said chambers and passages; a bellows secured to the under part of said block and communicating with one of said passages; and side plates secured to said laminated block.

2. A pneumatic unit constructed of five layers of material the lower layer having a depression in its upper face communicating with an opening in the tracker board and the upper layer having an air inlet port aligned with said depression and the central layer having a port aligned with said upper port; a diaphragm closing the upper end of said depression and having a post extending upwardly therefrom through the lower port; a bellows secured to the lower layer; a chamber in the next to the upper layer communicating with said bellows; a valve in said chamber normally closing the lower port and adapted by the upward movement of said diaphragm to be forced upwardly to close the upper port; and a walled chamber in the next to the bottom layer communicating with the vacuum chest.

3. A pneumatic unit constructed of five layers of material the lower layer having a depression in its upper face communicating with an opening in the tracker board and the upper layer having an air inlet port aligned with said depression and the central layer having a port aligned with said upper port; a diaphragm closing the upper end of said depression and having a post extending upwardly therefrom through the lower port; a bellows secured to the lower layer; a chamber in the next to the upper layer communicating with said bellows; a valve in said chamber normally closing the lower port and adapted by the upward movement of said diaphragm to be forced upwardly to close the upper port; a series of pins extending upwardly from the middle layer to prevent lateral displacement of said valve; and a walled chamber in the next to the bottom layer communicating with the vacuum chest.

4. A pneumatic unit constructed of five layers of material the lower layer having a depression in its upper face communicating with an opening in the tracker board and the upper layer having an air inlet port aligned with said depression and the central layer

having a port alined with said upper port; a diaphragm closing the upper end of said depression and having a post extending upwardly therefrom through the lower port; 5 a bellows secured to the lower layer; a chamber in the next to the upper layer communicating with said bellows; a valve in said chamber normally closing the lower port and adapted by the upward movement of said 10 diaphragm to be forced upwardly to close the upper port; a walled chamber in the next to the bottom layer communicating with the vacuum chest; and a small vent between the communicating passages to vacuum chest 15 and tracker bar.

5. A pneumatic unit constructed of five layers of material the lower layer having a depression in its upper face communicating with an opening in the tracker board and the 20 upper layer having an air inlet port alined with said depression and the central layer having a port alined with said upper port; a diaphragm closing the upper end of said depression and having a post extending upwardly therefrom through the lower port; 25 a bellows secured to the lower layer; a chamber in the next to the upper layer communicating with said bellows; a valve in said chamber normally closing the lower port and 30 adapted by the upward movement of said diaphragm to be forced upwardly to close the upper port; a walled chamber in the next to the bottom layer communicating with the vacuum chest; and a small vent be- 35 tween the communicating passages to vacuum chest and tracker bar so located that it may be cleared from obstructions without removal of the unit.

6. A pneumatic unit constructed of five 40 layers of material the lower layer having a depression in its upper face communicating with an opening in the tracker board and the upper layer having an air inlet port alined with said depression and the central layer 45 having a port alined with said upper port; a diaphragm closing the upper end of said depression and having a post extending upwardly therefrom through the lower port; a bellows secured to the lower layer; a chamber in the next to the upper layer communicating with said bellows; a valve in said 50 chamber normally closing the lower port and adapted by the upward movement of said diaphragm to be forced upwardly to close the upper port; pads of yielding material 55 on opposite sides of said valve; and a walled chamber in the next to the bottom layer communicating with the vacuum chest.

7. A pneumatic unit provided with upper 60 and lower chambers connected by a port and provided with an air inlet port alined with said connecting port; a bellows secured thereto and communicating with the upper chamber; a pipe leading from the lower 65 chamber to the vacuum chest; a depression

below the lower chamber; a diaphragm separating said depression from the lower chamber; a post extending upwardly from and movable with said diaphragm, said post extending to the top of the connecting port; 70 a valve normally closing the connecting port and adapted to be forced upwardly to close the inlet port; and a pipe from the tracker board communicating with said depression.

8. A pneumatic unit provided with upper 75 and lower walled chambers connected by a port and provided with an air inlet port alined with said connecting port; a bellows secured thereto and communicating with the upper chamber; a pipe leading from the lower chamber to the vacuum chest; a depression below the lower chamber; a diaphragm separating said depression from the lower chamber; a post secured to said diaphragm and extending to the top of the connecting port; a valve normally closing the connecting port and adapted to be forced upwardly to close the inlet port; resilient disks on opposite sides of said valve; and a pipe from the tracker board communicating with said depression. 80

9. A pneumatic unit provided with upper 85 and lower chambers connected by a port and provided with an air inlet port alined with said connecting port; a bellows secured 90 thereto and communicating with the upper chamber; a pipe leading from the lower chamber to the vacuum chest; a depression below the lower chamber; a diaphragm separating said depression from the lower chamber; a post extending upwardly from and movable with said diaphragm, said post extending to the top of the connecting port; 95 a valve normally closing the connecting port and adapted to be forced upwardly to close the inlet port; a pipe from the tracker board communicating with said depression; and parallel passages from the vacuum chest and tracker board pipes to the lower chamber and depression and connected by a small vent. 100

10. A pneumatic unit provided with upper 105 and lower chambers connected by a port and provided with an air inlet port alined with said connecting port; a bellows secured thereto and communicating with the upper 110 chamber; a pipe leading from the lower chamber to the vacuum chest; a depression below the lower chamber; a diaphragm separating said depression from the lower chamber; a post extending to the top of the connecting port; a valve normally closing the connecting port and adapted to be forced upwardly to close the inlet port; a pipe from the tracker board communicating with said depression; an inclined tubular member in 115 said block to receive the flexible pipe from vacuum chest; and a small vent beneath the inner end of said pipe communicating with said depression. 120

11. A pneumatic unit provided with upper 125 and lower chambers connected by a port and provided with an air inlet port alined with said connecting port; a bellows secured thereto and communicating with the upper chamber; a pipe leading from the lower chamber to the vacuum chest; a depression below the lower chamber; a diaphragm separating said depression from the lower chamber; a post extending to the top of the connecting port; a valve normally closing the connecting port and adapted to be forced upwardly to close the inlet port; a pipe from the tracker board communicating with said depression; an inclined tubular member in 130

- and lower walled chambers connected by a port and provided with an air inlet port alined with said connecting port; a bellows secured thereto and communicating with the upper chamber; a pipe leading from the lower chamber to the vacuum chest; a depression below the lower chamber; a diaphragm separating said depression from the lower chamber; a post extending upwardly from and movable with said diaphragm, said post extending to the top of the connecting port; a valve normally closing the connecting port and adapted to be forced upwardly to close the inlet port; and a tu-
5 bular member projecting upwardly from the front end of said block and communicating with the said depression, the upper end of which is adapted to receive the end of a flexible pipe from the tracker board.
- 10 12. A pneumatic unit provided with upper and lower walled chambers connected by a port and provided with an air outlet alined with said connecting port; a bellows secured thereto and communicating at its larger end with the upper chamber; a pipe leading from the lower chamber to the vacuum chest; a depression below the lower chamber; a dia-
15 phragm separating said depression from the lower chamber; a post extending upwardly from and movable with said diaphragm, said post extending to the top of the connecting port; a valve normally closing the connect-
20 ing port and adapted to be forced upwardly to close the inlet port; and a pipe from the tracker board communicating with said de-
25 pression.
- 20 12. A pneumatic unit provided with upper and lower walled chambers connected by a
- port and provided with an air outlet alined with said connecting port; a bellows secured thereto and communicating at its larger end with the upper chamber; a pipe leading from the lower chamber to the vacuum chest; a depression below the lower chamber; a dia-
30 phragm separating said depression from the lower chamber; a post extending upwardly from and movable with said diaphragm, said post extending to the top of the connecting port; a valve normally closing the connect-
35 ing port and adapted to be forced upwardly to close the inlet port; and a pipe from the tracker board communicating with said de-
35 pression.
